UNITED STATES PATENT OFFICE.

WARREN HERBERT FROST, OF CLEVELAND, OHIO.

GARMENT-SUPPORTER.

SPECIFICATION forming part of Letters Patent No. 331,392, dated December 1, 1885.

Application filed January 21, 1885. Serial No. 153,542. (No model.)

To all whom it may concern:

Be it known that I, WARREN HERBERT FROST, a citizen of the United States, residing at Cleveland, in the county of Cuyahoga and 5 State of Ohio, have invented a certain new and useful Garment-Supporter, of which the following is a specification.

My invention relates to improvements in garment - supporters adapted to encircle the 10 limb and having one or more clasps attached thereto; and the objects of my invention are, first, to provide a garment-supporter that shall set smoothly and comfortably on the limb and be of neat and attractive appearance; second, 15 to provide such a garment-supporter that may be quickly and easily put on and detached, and be economical to manufacture. I attain these objects by means illustrated in the accompanying drawings, in which—

20 Figure 1 represents the garment-supporter without means of detaching the parts. Fig. 3 shows the garment-supporter with hook E and ring D, for quickly separating or attaching the parts; and Fig. 2 shows a garment-supporter 25 having two clasps attached.

Similar letters refer to similar parts throughout the several views.

The piece A is made of cloth shaped, preferably, in a triangular form, and has a clasp, 30 C, attached to one corner, the other two corners being secured either by permanent or detachable means to a band, B, intended to encircle the limb and made preferably of elastic.

As a means of convenience in attaching to 35 or detaching from the limb, I attach a hook, E, to the end of the band B, and a ring, D, to an elastic loop attached to one corner of the

piece A. Though I prefer this method of separation other means could be employed.

I prefer to use one clasp, C, as shown in Figs. 40 1 and 3, though two or more clasps could be attached, as C and C', in Fig. 2.

By having a smooth piece of material, A, connecting the ends of the band B and clasp or clasps C, I obtain a neat and elegant appearance, and by doing away with all cords, 45 seamed webbing, &c., insure comfort and durability, together with economy of manufacture.

I am aware that other garment-supporters encircling the limb and having clasps attached thereto have been and are made; and I am aware that garment-supporters consisting of a belt and dependent pieces with garment-clasps attached have been made, and do not claim such; but 55

What I claim as my invention, and desire to have protected by Letters Patent, is—

1. In a garment-supporter adapted to encircle the limb, a band formed by the combination of a strip of elastic webbing and a piece 60 of cloth, said cloth arranged substantially as described, and having one or more garment-clasps attached thereto, substantially as shown and described.

2. In a garment-supporter adapted to encircle the limb, the combination of the piece 65 of cloth A, one or more clasps, C, and the band B, with a device for separating one end of the band B from the piece A.

WARREN HERBERT FROST.
